US0D1098258S

(12) United States Design Patent (10) Patent No.: US D1,098,258 S
Clarke (45) Date of Patent:  Oct. 14, 2025

(54) TYPE FONT

(71) Applicant: Lotus Bakeries International und Schweiz AG, Baar (CH)

(72) Inventor: Rob Clarke, Hertfordshire (GB)

(73) Assignee: LOTUS BAKERIES
INTERNATIONAL UND SCHWEIZ
AG, Baar (CH)

() Term: 15 Years

(21) Appl. No.: 29/930,639

(22) Filed: Mar. 1, 2024

(51) LOC (15) Cl. 18-03

(52) U.S. Cl.

USPC D18/24

(58) Field of Classification Search

USPC D18/24
CPC B41B 1/02; G09B 1/04; G09B 3/04
